UNITED STATES PATENT OFFICE

141,513

DESIGN FOR A NAPKIN OR THE LIKE

Henrietta Scott, Pequea, Pa.

Application March 10, 1945, Serial No. 118,396

Term of patent 7 years

(Cl. D92—26)

To all whom it may concern:

Be it known that I, Henrietta Scott, a citizen of the United States, residing in Fox Hollow, Pequea, Lancaster County, State of Pennsylvania, have invented a new, original, and ornamental Design for a Napkin or the like, of which the following is a specification, reference being had to the accompanying drawing forming part thereof, in which the figure is a face view of a napkin or the like, showing my new design.

I claim:

The ornamental design for a napkin or the like, as shown.

HENRIETTA SCOTT.
